(57) **CLAIM**

The ornamental design for a docking station with stand, as shown and described.

DESCRIPTION

FIG. 1 is a front, right and top perspective view of a docking station with stand showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a front perspective view of a docking station with stand, showing in a configuration of use in an environment of use.

The broken lines shown in the figures are for the purpose of illustrating portions of the docking station with stand in an environment of use, which form no parts of the claimed design.
